UNITED STATES PATENT OFFICE.

HAROLD G. WARR, OF CHICAGO, ILLINOIS, ASSIGNOR TO THE P & M COMPANY, OF CHICAGO, ILLINOIS, A CORPORATION OF ILLINOIS.

RAIL-ANCHOR.

1,274,825.

Specification of Letters Patent.

Patented Aug. 6, 1918.

Continuation in part of application Serial No. 858,230, filed August 24, 1914. This application filed June 3, 1916. Serial No. 101,433.

To all whom it may concern:

Be it known that I, HAROLD G. WARR, a citizen of the United States, residing at Chicago, in the county of Cook and State 5 of Illinois, have invented certain new and useful Improvements in Rail-Anchors, of which the following is a specification.

My invention relates to devices for preventing the longitudinal creep of railroad 10 rails, such devices being commonly known as anti-creepers, creep-checks or rail-stays.

The principal object of the invention is to provide a device of this type which will be simple in its construction, inexpensive to 15 manufacture, light in weight, strong and capable of taking a firm and reliable hold on the rail, which will not be disturbed by vibration or other causes tending to loosen the grip of rail anchors on the rails engaged 20 thereby.

A further object is to provide a device which may be quickly and conveniently applied to or disengaged from the rail.

The invention is illustrated in two typical embodiments. In one of these embodiments the device is composed of two elements, one of which may be termed a rail-gripping or engaging element, and the other a tie-engaging element. The tie-engaging 25 element bears against the side face of a tie or other stationary part of the roadbed and has a wedging relation with the rail and rail-engaging element. Inasmuch as my invention contemplates making and constructing the rail-engaging element so that its hold on the rail is not entirely dependent upon the wedging relation with the other element just mentioned, it is possible to omit the separate tie-engaging member entirely, 30 in which case the rail-engaging element bears immediately against the tie. The second embodiment of the invention consists, therefore, of a one-piece rail anchor or anti-creeper so constructed that when applied 35 to the rail it will take a hold upon the same sufficient, when the device is abutted against a tie, to check the tendency of the rail to creep.

In the drawings Figure 1 is a longitudinal, sectional view taken through the two-piece device, which is shown as applied to a rail and abutted against one of the cross-ties upon which the rail is supported.

Fig. 2 is a cross-sectional elevation on line 2—2 of Fig. 1, but showing the device in 55 process of application to the rail.

Fig. 3 is a similar view showing the device in operative position on the rail.

Fig. 4 is a view in perspective of the tie-abutting or wedge member of the two-piece 60 rail anchor.

Fig. 5 is a similar view of the rail-engaging member.

Fig. 6 is a plan view with the web of the rail in section, illustrating the use of the 65 rail-engaging member as a one-piece anchor.

Fig. 7 is a view of the device illustrating its application to the rail, and

Fig. 8 a view similar to Fig. 7, with the device in operative position. 70

Like characters of reference indicate like parts in the several figures of the drawings.

Referring first to Figs. 1 to 5 inclusive, the tie-abutting member A consists of a flat piece of metal, preferably steel, having 75 pressed therein, preferably, a tapering rib. One end of the piece of metal is bent over to form a tie-abutting plate or foot 11. The other is bent up as indicated at 12.

The rail-engaging member B consists of 80 a bar of metal, preferably steel, with one end bent over to form a jaw 13, and the other end bent to form a somewhat longer jaw 14. The bar, which is generally bowed in its configuration, is bent somewhat sharply to provide an upward projection 15. This projection is preferably at a point adjacent the jaw 14. At about the middle of the bar another bend 16 is formed providing a hollow or recess 17 in the upper surface of the bar. The extremity of the bar forming the jaw 14 is preferably off-set so as to provide a shoulder 18. The other jaw 13 is provided on opposite sides with recesses 19 shaped to take the claw of a claw bar. The inner face of jaw 13 is preferably beveled off as shown at 20.

The application of the device to the rail, shown in the drawings at C, is as follows: The jaw 14 of the rail-engaging member B 100 is hooked over one edge of the base flange of rail C and the tie-abutting wedge member A is placed between the base flange and the rail-engaging member with its tie-abutting plate 11 against tie D. Fig. 2 shows 105 the arrangement of the parts. The other

end of the rail-engaging member B is then raised, for example, by means of a claw bar E and the device is forced or driven endwise, bringing jaw 13 into engagement with the edge of the base flange of the rail adjacent thereto. The jaw, it will be seen, engages both the upper and lower surfaces of the rail base. I contemplate a close fit of jaw 13 on the edge of the rail base. The movement of the rail-engaging member transversely of the rail causes the edge of the rail engaged by jaw 14 to seat behind the shoulder formed on the under surface of the jaw. At the same time the rib 10 on the tie-abutting member is engaged by the groove or recess 17 in the upper surface of the rail-engaging member. The application of the device to the rail is facilitated by the beveled surface 20 on jaw 13 which comes against the upper edge of the rail base on this side of the rail.

The application of the device to the rail involves, in the first place, the bending of the tie-abutting member. This produces a stress between the device and the rail which is enhanced by any tendency on the part of the rail to creep, due to the fact that the tie-abutting member, because of the taper of rib 10, is in effect a wedge. In the second place, the rail-engaging member itself is subject to a bending strain when applied to the rail. The jaws 13 and 14 are in effect obliquely disposed in respect to each other, the jaw 14 having a downward inclination with respect to the jaw 13, which is substantially horizontal when the device is in its operative position. In other words, the rail-engaging member when applied to the rail is deformed slightly at opposite sides of its bearing point 15 on the bottom of the rail base. This deformation and consequent binding action of the rail-engaging member on the rail is quite independent of the tie-engaging member, the effect of the latter being simply to enhance the grip of the rail-engaging member on the rail. It is, therefore, possible to eliminate the tie-abutting element and use the rail-engaging element alone to form a one-piece anti-creep, as shown in Figs. 6 to 8 inclusive. The rail-engaging member in such case lies flatwise against the tie and depends for its hold on the rail on the bending strain to which it is subjected in being applied thereto.

It will be seen that a rail anchor constructed as shown, whether it be a two-piece device or a one-piece device, has a resilient hold on the rail which is not loosened by vibration or likely to be affected by other accidental disturbances. The effectiveness of the hold on the rail is not dependent upon bolts or upon wedge action, although the wedging relationship between the parts of the device in the two-part anchor acts to in-

crease the grip of the device on the base of the rail. The rail anchor in either form is inexpensive to manufacture and very easily applied to the rail and as easily removed therefrom when occasion demands. With one edge of the rail base jammed firmly into jaw 13 and the other edge abutting on shoulder 18 formed on the other jaw, there is no chance for the rail-engaging member to be displaced transversely of the rail, particularly as any such disturbance of the device from its normal position is resisted by the bending stress constantly exerted against it. When the element B is used alone as a one-piece anchor it will be seen that the pressure of the device against the tie taking place when the creeping stress is exerted on the rail tends to tighten the hold of the device on the rail so that the creeping tendency is self checked.

This application is a continuation in part of my co-pending application Serial No. 858,230, filed August 24, 1914, (patented February 27, 1917, No. 1,217,541,) the form of the invention shown in Figs. 1 to 4, inclusive, herein being shown in Figs. 6, 7, 8 and 9 of the earlier application.

I claim:

1. A device for preventing the longitudinal creep of a railroad rail, comprising a bar of resilient metal adapted to extend under the base flange of the rail and to be strained by application thereto so as to be under spring tension when engaged therewith, formed at one end with a jaw adapted to fit over one edge of the base flange and bear with a snug fit against both upper and lower surfaces thereof at substantially opposite points, the bar being formed with a bend which bears against the under surface of the base flange and the other extremity extending around and bearing against the upper surface of the base flange on the opposite side from the first-mentioned jaw.

2. A device for preventing the longitudinal creep of a railroad rail, comprising a bar adapted to extend under the base flange of the rail, formed at one end with a jaw adapted to fit over one edge of the base flange, bearing against both upper and lower surfaces thereof, the bar being formed near its other extremity with a bend which bears against the under surface of the base flange adjacent said extremity extending around and bearing upon the upper surface of the rail base.

3. A device for preventing the longitudinal creep of a railroad rail, comprising a bar adapted to extend under the base flange of the rail, formed at one end with a jaw adapted to fit over one edge of the base flange bearing against both upper and lower surfaces thereof, the bar being formed with a bend which bears against the under sur-

face of the base flange and the other extremity extending around and bearing against the upper surface of the base flange on the opposite side from the first-mentioned jaw, the under surface of said extremity of the bar being formed with a shoulder adapted to bear against the edge of the rail base.

4. A device for preventing the longitudinal creep of railroad rails, comprising a member adapted to be strained by application of the device to the rail and which extends under the rail and is provided at opposite ends with jaws adapted to engage opposite edges of the base flange thereof, one of said jaws being formed so that it takes a cramping or pinching hold upon the rail base, and the other jaw being formed to wedgingly engage the opposite edge of the said rail base.

5. A device for preventing the longitudinal creep of railroad rails, comprising a resilient member adapted to be strained by application of the device to the rail and which extends under the rail and is provided at opposite ends with jaws adapted to engage opposite edges of the base flange thereof, one of said jaws being formed so that it takes a cramping or pinching hold upon the rail base, and the other jaw being formed to wedgingly engage the opposite edge of said rail base.

6. A device for preventing the longitudinal creep of a railroad rail, comprising a member adapted to be strained by application of the device to the rail and which extends under the rail and is provided at opposite ends with jaws adapted to engage opposite edges of the base flange thereof, one of said jaws being formed so that it takes a cramping or pinching hold on the rail base, and the other jaw being formed to wedgingly engage the opposite edge of said rail base, the distance between the interior surfaces of said jaw being greater than the width of the rail base, for the purpose described.

7. A device for preventing the longitudinal creep of a railroad rail, comprising a bar of slightly resilient metal provided at opposite ends with rail base engaging jaws, said bar being formed with a bend whereby one of said jaws has a cramping or pinching grip on the rail base when the device is applied thereto, and the other jaw being formed so as to wedgingly engage the opposite edge of the rail base.

8. A device for preventing the longitudinal creep of a railroad rail, comprising a bar of slightly resilient metal provided at opposite ends with rail base engaging jaws, said bar being formed with a bend whereby one of said jaws has a cramping or pinch-

ing grip on the rail base when the device is applied thereto, and the other jaw being formed so as to wedgingly engage the opposite edge of the rail base, the distance between the interior surfaces of said jaws being greater than the width of the rail, for the purpose described.

9. A device for preventing the longitudinal creep of a railroad rail, comprising a bar of slightly resilient metal provided at opposite ends with rail base engaging jaws, said bar being formed with a bend whereby one of said jaws has a cramping or pinching grip on the rail base when the device is applied to the rail, and formed on the under side thereof with a shoulder against which the edge of the base flange of the rail is adapted to bear, the other jaw being formed to have a wedging engagement with the opposite edge of the rail.

10. A device for preventing the longitudinal creep of a railroad rail, comprising a bar of slightly resilient metal provided at opposite ends with rail base engaging jaws, said bar being formed with a bend whereby one of said jaws has a cramping grip on the rail base when the device is applied to the rail and the other jaw being formed so as to have a wedging engagement with the opposite edge of the rail and provided with a recess for a claw bar, the distance between the interior surfaces of said jaws being greater than the width of said base flange, for the purpose described.

11. A device for preventing the longitudinal creep of a railroad rail, comprising a bar adapted to extend under the base flange of the rail and engaging the upper surfaces of the same on opposite sides of the rail, and having a cramping engagement with the undersurfaces thereof at places adjacent the edges of the base flange, said member being resilient and formed so as to be strained when applied to the rail.

12. A device for preventing the longitudinal creep of a railroad rail, comprising a bar adapted to extend under the base flange, formed with jaws at opposite ends which engage the base flange of the rail at four separate places, two on the upper surface thereof and two on the lower surface, said member being resilient and formed so that it is strained when applied to the rail.

13. A device for preventing the longitudinal creep of a railroad rail, comprising a resilient bar the ends of which are in the form of jaws engaging the upper and lower surfaces of the base flange of the rail at opposite edges and the portion between said jaws standing away from said base flange, said bar being formed so that it is strained when applied to the rail.

14. A device for preventing the longi-

tudinal creep of a railroad rail, comprising a resilient bar the ends of which are in the form of jaws engaging the upper and lower surfaces of the base flange of the rail at 5 opposite edges and the portion between said jaws standing away from said base flange, said bar being formed so that it is strained when applied to the rail, the distance be-

tween the jaws being greater than the width of the rail base and the part of one of the 10 jaws bearing on the upper surface of the rail base being recessed to form a shoulder which bears against the edge of said rail base.

HAROLD G. WARR.
